CLAIM

The ornamental design for a household beer storage container, as shown and described.

DESCRIPTION

1. Household beer storage container

1.1 : Perspective

1.2 : Front

1.3 : Left

1.4 : Top

1.5 : Bottom

The fine lines on the drawings indicate the flat surface or curved surface; reproduction 1.1 is a front perspective view of the household beer storage container; reproduction 1.2 is a front view thereof where the back view is a mirror image; reproduction 1.3 is a left view thereof where the right view is a mirror image; reproduction 1.4 is a top view thereof; reproduction 1.5 is a bottom view thereof; this is a design for a household beer storage container made of synthetic resin

(Continued)

and metal that can be stacked; the claimed design has a hole that can drain water on the lower edge of the upper handle.
